DEVICE FOR PRODUCING ELECTRIC PULSES,
PARTICULARLY FOR MEDICAL PURPOSES

Felix Schuhfried, Vienna, Austria

Application January 21, 1949, Serial No. 71,968
In Austria June 30, 1948

13 Claims. (Cl. 128—422)

1
The present invention relates to a device for producing electrical pulses, particularly for purposes of medical therapy, such as, for instance, the treatment of paralysis, or for purposes of diagnostic, e. g., to determine the electrical excitability of a patient.

The invention contemplates to provide a device for producing electrical pulses for purposes of medical therapy and/or diagnostic which is adaptable to varying requirements and which in spite of a relatively simple construction will enable not only the attending physician but also the patient himself to make the adjustments necessary for obtaining electrical pulses of such kind as will be best to suit the requirements in each particular field of application. Accordingly it is an object of the invention to make possible the production of pulses the duration of which is controllable and whose intervals and curve slope, i. e., rise time, are adjustable.

A further object of the invention is to provide a device for producing electrical pulses for the purposes above indicated wherein a change of the adjustment of the duration of the pulses will bring about an approximately proportional change of the rise time without requiring any separate manipulation for that latter change.

A further object of the invention is to provide a device of the kind referred to which is capable of producing electrical pulses in periodical sequence as well as individual pulses, a key or the like being provided for the latter purpose.

A further object of the invention is to provide a device of the kind referred to enabling the patient, even if bedridden, to bring into play, such as by pressing a key, electrical pulses whose rise time has been previously adjusted by the physician.

Still a further object of the invention is to provide a device of the kind referred to wherein the amplitude of the electric pulses can be controlled by the patient himself so that the intensity of these pulses will increase and decrease as desired.

Finally, it is an object of the invention to provide a device of the kind referred to having means for automatically increasing and decreasing the amplitude of the pulses.

Other objects of the invention will appear as the description proceeds, reference being had to the accompanying drawing, in which:

Fig. 1 shows by way of example a circuit diagram of an embodiment of the invention;

Fig. 2 illustrates a modification of a portion of the circuit of Fig. 1; and

Fig. 3 shows another modification.

2
The two tubes B_1 and B_2 are connected in a manner well known as a multivibrator, the tube B_1 being a triode whereas for the tube B_2 a pentode is used so that a disturbing reaction of the output circuit on the operation of the multivibrator is avoided. As conventional, the plate of the tube B_1 is connected across a condenser C_1 to the control grid of the tube B_2 which in turn is connected to the cathode of this tube B_2 across a resistor R_1 . The screen grid of the tube B_2 is included into the multivibrator circuit by being connected through the condenser C_2 with the grid of the tube B_1 ; the coordinated grid leak being indicated at R_2 . Since the mode of operation of a multivibrator is well known to those skilled in the art no detailed description thereof is deemed to be necessary here. Due to the alternating blocking of the two tubes according to the multivibrator principle there is created at the plate 20 resistor R_A of the pentode B_2 a periodical series of pulses whose duration or width is determined substantially by the time constant $T_1=R_1C_1$ whereas for the interval between the pulses the time constant $T_2=R_2C_2$ is determinative. Due to the electronic coupling of the output circuit with the multivibrator circuit proper through the intermediary of the pentode B_2 a disturbing reaction of the output circuit upon the shape of the pulses, the pulse duration and the interval between the pulses of the multivibrator is avoided.

The output pulses of the multivibrator which develop at the resistor R_A are supplied by means of a voltage divider comprising resistors R_5 and R_6 to a time-constant network comprising a resistor R_3 and a condenser C_3 . The condenser C_3 is arranged between the grid and the cathode of an output tube B_3 in whose plate circuit there are arranged electrodes E to be applied to the patient for purposes of diagnosis or for therapeutical treatment. It will be obvious to those skilled in the art that the electrodes E may be shunted by a current limiting device, e. g. a resistor (not shown), to limit the current passing through the body of the patient. The time-constant network R_3, C_3 causes a change of the shape of the pulses by changing the slope of the pulse curve. For the same purpose there may be used an RL-network (resistor-inductance network) instead of an RC network (resistor-capacitance network).

According to the invention the time constants $T_1=R_1C_1$, $T_2=R_2C_2$ and $T_3=R_3C_3$ are made variable in order to be able to adjust the pulse duration (through T_1), the duration of the intervals between the pulses (through T_2) and the

slope of the pulse rise (through T_3) to suit the medical requirements of each particular case. The variability of the time constants may be made possible by making either the condensers C_1, C_2, C_3 or the resistors R_1, R_2, R_3 or both the 5 condensers and the resistors either continuously variable or switchable from one value to another. It has been found most suitable to make the capacitances switchable and the resistors continuously variable. In the example shown, the resistors R_1, R_2 , and R_3 are indicated by arrows to be variable resistors.

Another possibility for the control of the slope of the pulses is indicated in Fig. 2. In order to avoid possible distortions through the setting-in 15 of grid current and a counter potential occasioned thereby at certain values of R_3 , the latter is made constant and a variable resistor R_4 is arranged between the grid and the cathode of the tube B_3 , which variable resistor R_4 is in 20 series with the condenser C_3 .

For the medical application of the device it is important that with a variation of the pulse duration there goes a simultaneous regulation of the rise time of the pulse. To achieve this, the adjusting element which controls the time constant T_1 determining the duration of the pulses is mechanically coupled with the adjusting element for the time constant T_3 which determines the rise time of the pulses. Fig. 1 shows for that purpose in parallel to the variable resistor R_3 a further variable resistor R_3' which, as indicated by a dotted line, is mechanically coupled with the variable resistor R_1 . Thus the time constant T_3 is determined by the resistance resulting from the parallel connection of the resistors R_3 and R_3' , and by the capacitance C_3 . With this arrangement the time constant T_3 which determines the rise time varies in the same sense as the time constant T_1 which determines the pulse duration. It is also possible to leave out the resistor R_3' and to provide a mechanical coupling between the variable resistors R_1 and R_3 .

The variable resistor R_4 shown in Fig. 2 is to be understood as being coupled with the variable resistor R_1 of Fig. 1.

The invention further contemplates to adapt the described device for the generation of individual pulses. For that purpose the multivibrator is transformed into an electronic switch by interrupting the feed-back from the second tube B_2 to the first tube B_1 and by a suitable voltage control of the first tube B_1 . To interrupt the feedback there is provided in Fig. 1 a switch S_2 , which separates the coupling condenser C_2 from the screen grid of the tube B_2 . Simultaneously with the switch S_2 , the switch S_1 is closed in order to supply across the resistor R_7 a blocking negative bias to the grid of the tube B_1 . If now, by closing of the switch S_3 , a positive voltage derived from the voltage divider R_8, R_9 is applied to the grid of the tube B_1 so that this tube becomes conductive and draws current, a voltage pulse is transmitted through the time-constant network C_1, R_1 to the control grid of the pentode B_2 , the duration of the pulse being determined by the time-constant $T_1=R_1 \cdot C_1$ and being adjustable in the manner previously described. Due to the already mentioned mechanical coupling of the adjusting elements for the time constants T_1 and T_3 , the rise time of the pulses may be influenced simultaneously with the duration of the pulses.

For the medical applicability it is important

that the patient be not caught unaware by an electric pulse, but that he may release the pulse himself whereby a cooperation between will impulse and electrical impulse is achieved, which is essential for the therapy of paralysis. With this in view, there is provided a small switch case P which the patient lying in bed may easily operate and which will permit him to choose himself the moment and the strength of the pulse application. To fix the moment when the pulse is to be applied the switch S_3 or a switch contact in parallel thereto may be placed in the switch case mentioned or there may be provided suitable actuating contacts at other points of the circuit. According to Fig. 1 there is provided in the patient's switch case P a switch S_4 which enables the release of individual pulses of variable rise time. Prior to the actuation of the switch S_4 the multivibrator is cut out by applying to the control grid of the tube B_1 a blocking negative voltage by means of the switch S_1 . Then a positive voltage derived from the voltage divider R_8, R_9 can be applied by means of the switch S_4 to the time constant network R_3, C_3 which, in the manner described above, causes a voltage pulse in the circuit including the patient which pulse may be adjusted through adjustment of the time constant T_3 . In the patient's switch case P there is further provided a variable resistor R_{10} for adjusting the amplitude of the individual pulses or of the periodic output pulses of the multivibrator so that the patient himself may select the intensity of the impulses and, in particular, make this intensity rise and fall. The variable resistor R_{10} may be connected, e. g., into the screen grid circuit of the pentode B_3 .

Automatic increase and decrease of the intensity of the pulses may be obtained by applying to the screen grid of the pentode B_3 an alternating voltage which controls the amplification, which voltage may be derived from a second multivibrator and effects a modulation of the output pulses. Such an arrangement is shown in Fig. 2 according to which the screen grid of the tube B_3 is connected across a resistor R_{11} and the secondary of a transformer T to the positive terminal of the voltage source. To the primary of the transformer T there is applied the modulating alternating voltage. Screen grid modulation may also be obtained in the manner shown in Fig. 3 by connecting the screen grid of tube B_3 with the plate of another tube B_4 whose grid is supplied with a control voltage having the desired modulating frequency.

To those skilled in the art, it will be obvious that various changes may be made in the details of the circuit without departing from the spirit of the invention. For example, the time constant network T_3 might be arranged in parallel to the electrodes E , as is shown in Fig. 3.

In order to be able to apply direct current to the patient, there may be provided a switch S_5 across which the grid of the tube B_2 obtains a negative bias, whereby this tube is blocked and tube B_3 becomes conductive.

What I claim is:

1. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a first time-constant network for controlling the duration of the pulses, by a sec-

ond time-constant network for controlling the intervals between the pulses, of which said two time-constant networks one at least is variable, and also by a third time-constant network adapted to receive the output pulses of the multivibrator and being variable for controlling the rise time (slope of the curve) of the output pulses, and means for connecting the output of said multivibrator circuit to two electrodes adapted to be applied to the body of the patient.

2. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a variable first time-constant network for controlling the duration of the pulses, by a second time-constant network for controlling the intervals between the pulses, and also by a third time-constant network adapted to receive the output pulses of the multivibrator and being variable for controlling the rise time of the output pulses, the means for varying the time-constant of said network determining the duration of the pulses being mechanically coupled with the means for varying the time-constant of said third network determining rise time of the output pulses, and means for connecting the output of said multivibrator to electrodes adapted to be applied to the body of the patient.

3. A device as defined in claim 2, wherein a variable resistor for varying the duration of the pulses is mechanically coupled with a variable resistor for varying the rise time of the output pulses.

4. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a first time-constant network for controlling the duration of the pulses, by a second time-constant network for controlling the intervals between the pulses, of which said two time-constant networks one at least is variable, and also by a third time-constant network adapted to receive the output pulses of the multivibrator and being variable for controlling the rise time of the output pulses, an electron tube having a cathode, a plate and at least a control grid in addition to said two tubes of the multivibrator, said third network including a resistance in series with a capacitor, the latter being arranged between said control grid and said cathode of said additional electron tube, and means for connecting the output of said multivibrator to electrodes adapted to be applied to the body of the patient.

5. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a first time-constant network having at least one variable element for controlling the duration of the pulses, by a second time-constant network for controlling the intervals between the pulses, and also by a third time-constant network adapted to receive the output pulses of the multivibrator and being variable for controlling the rise time of the output pulses, an electron tube having a cathode, a plate and at

least a control grid in addition to said two tubes of the multivibrator, said third network for controlling the rise time of the output pulses including a resistance in series with a capacitor, said resistance comprising two resistors in parallel of which one at least is variable and mechanically coupled with said variable element of said first network for controlling the duration of the pulses, and said capacitor being arranged between said control grid and said cathode of said additional electron tube, and means for connecting the output of said multivibrator to electrodes adapted to be applied to the body of the patient.

6. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a first time-constant network including a variable resistor for controlling the duration of the pulses, by a second time-constant network including a variable resistor for controlling the intervals between the pulses, and also by a third time-constant network adapted to receive the output pulses of the multivibrator and being variable for controlling the rise time of the pulses, an electron tube having a cathode, a plate and at least a control grid in addition to said two tubes of the multivibrator, said third time-constant network for controlling the rise time of the pulses comprising the series connection of a resistor and an impedance, said impedance being connected between said grid and said cathode of said additional electron tube and containing a condenser and a variable resistor, the latter being mechanically coupled with said variable resistor of said first time-constant network controlling the duration of the pulses, and means for connecting the output of said multivibrator to electrodes adapted to be applied to the body of the patient.

7. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a first time-constant network for controlling the duration of the pulses, by a second time-constant network for controlling the intervals between the pulses and also by a third time-constant network adapted to receive the output pulses of the multivibrator and being variable for controlling the rise time of the output pulses, and two electrodes adapted to be applied to the body of the patient, said third time-constant network for controlling the rise time of the output pulses being arranged in parallel to said electrodes.

8. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a variable first time-constant network for controlling the duration of the pulses, by a variable second time-constant network for controlling the intervals between the pulses, and also by a third time-constant network adapted to receive the output pulses of the multivibrator and being variable for controlling the rise time of the output pulses, means for transforming the multivibrator circuit into an electronic

switch circuit comprising two switches, one of said two switches being adapted to interrupt the feedback from said second tube to said first tube and the other of said two switches being adapted to apply a cut-off voltage to the grid of said first tube, means for actuating the electronic switch to release individual pulses whose duration and rise time are adjustable by means of said first and third time-constant network comprising a switch so connected into the circuit as to apply a positive voltage to the grid of said first tube and means for connecting the output of said multivibrator to electrodes adapted to be applied to the body of the patient.

9. A device for producing electrical pulses for purposes of medical therapy and/or diagnostic, comprising, in combination, a multivibrator circuit having a first and a second thermionic tube, each including a cathode, a plate and at least one grid therebetween, said two thermionic tubes being interconnected by a variable first time-constant network for controlling the duration of the pulses, by a variable second time-constant network for controlling the intervals between the pulses, and also by a third time-constant network adapted to receive the output pulses of the multivibrator and being variable for controlling the rise time of the output pulses, means for releasing individual pulses including two switches of which one is adapted to apply a negative cut off potential to the control grid of said first tube and the other switch is adapted to transmit a voltage pulse to said third time-constant network, and means for connecting the output of said multivibrator to electrodes adapted to be applied to the body of the patient.

10. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a variable first time-constant network for controlling the duration of the pulses, by a variable second time-constant network for controlling the intervals between the pulses of which said two time-constant networks one at least is variable, and also by a third time-constant network adapted to receive the output pulses of the multivibrator and variable for controlling the rise time of said output pulses, means for controlling the amplitude of said output pulses, and means for connecting the output of said multivibrator to electrodes adapted to be applied to the body of the patient.

11. A device for producing electrical pulses for purposes of medical therapy and/or diagnostic, comprising, in combination, a multivibrator circuit having a first and a second thermionic tube, each including a cathode, a plate and at least one grid therebetween, said two thermionic tubes being interconnected by a variable first time-constant network for controlling the duration of the pulses, by a variable second time-constant network for controlling the intervals between the pulses and also by a third time-constant network

adapted to receive the output pulses of the multivibrator and being variable for controlling the rise time of the output pulses, means for transforming the multivibrator circuit into an electronic switch circuit comprising two switches, one of said two switches being adapted to interrupt the feedback from said second tube to said first tube and the other of said two switches being adapted to apply a cut-off voltage to the grid of said first tube, means for actuating the electronic switch to release individual pulses whose duration and rise time are adjustable by means of said first and third time-constant networks, comprising a switch so connected into the circuit as to apply a positive voltage to the grid of said first tube, means for controlling the amplitude of said output pulses, and means for connecting the output of said multivibrator to electrodes adapted to be applied to the body of the patient, said means for releasing individual pulses and said means for controlling the amplitude thereof being situated in a switch case arranged so as to be easily operable by the patient.

12. A device as claimed in claim 1, having means for modulating the output pulses.

13. A device for producing electrical pulses for purposes of medical therapy and/or diagnostic, comprising, in combination, a multivibrator circuit having two thermionic tubes each including a cathode, a plate and at least one grid therebetween, said two thermionic tubes being interconnected by a variable first time-constant network for controlling the duration of the pulses, by a variable second time-constant network for controlling the intervals between the pulses and also by a third time-constant network adapted to receive the output pulses of the multivibrator and being variable for controlling the rise time of the output pulses, an electron tube in addition to said two tubes of the multivibrator, said additional electron tube having a cathode, a plate, and at least a control grid and a screen grid between said cathode and plate, means for modulating said output pulses including a transformer whose primary is adapted to be connected to a source of alternating modulating voltage and whose secondary is connected into the screen grid-plate circuit of said additional tube, and means for connecting the output of said multivibrator to electrodes adapted to be applied to the body of the patient.
